ARTICLE HANDLING APPARATUS

Carl J. Hackbarth and Carl V. Lundeen, Baltimore, Md., assignors to Western Electric Company, Incorporated, New York, N. Y., a corporation of New York

Application October 30, 1935, Serial No. 47,360

12 Claims.

(Cl. 10—162)

This invention relates to article handling apparatus, and more particularly to feeding mechanisms for feeding small parts to a punch press.

It is an object of the present invention to provide a simple automatic feeding mechanism for article forming apparatus.

In accordance with one embodiment, the invention contemplates the provision of a chute for feeding headed parts to an oscillating member which will receive one part from the chute and will be oscillated in timed relation to the step-by-step rotation of a dial to move the article to a position above an article receiving portion of the dial, a plate being provided beneath the oscillating member to prevent the article being fed from dropping through the oscillating member until the slot in the oscillating member and the article receiving slot in the dial reach a predetermined position where they are in direct alignment.

A better understanding of the invention will be had from the following detailed description when considered in conjunction with the accompanying drawings, wherein

Fig. 1 is a front elevational view of a punch press having a rotatable dial and being provided with a feeding mechanism forming the subject matter of the present invention;

Fig. 2 is a fragmentary sectional view taken on the line 2—2 of Fig. 1 in the direction of the arrows;

Fig. 3 is a sectional view taken substantially along the line 3—3 of Fig. 2 in the direction of the arrows;

Fig. 4 is a fragmentary sectional view taken on the line 4—4 of Fig. 3 in the direction of the arrows showing the construction of the chute;

Fig. 5 is a fragmentary sectional view taken on the line 5—5 of Fig. 3 in the direction of the arrows showing a detail of construction of the oscillatable member, and

Fig. 6 is a developed sectional view taken on the line 6—6 of Fig. 2 in the direction of the arrows.

Referring now to the drawings wherein like reference characters indicate like parts throughout the several views, the numeral 10 (Fig. 1) designates generally a punch press having a base 11 of any suitable type upon which are mounted a bed 12 and uprights 13—13. The uprights support and guide a reciprocating ram 14 which is operated in the usual manner by a crank 15 formed on a shaft 16, a fly wheel 17 secured to the shaft insuring regularity of operation. Fixed to the shaft 16 upon the end thereof opposite to

the end upon which the fly wheel is mounted is an indexing crank wheel 23. In the usual manner the indexing crank wheel 23 operates a rod 24 pivotally secured to one arm of a bell crank lever 25 which is pivoted upon the base 11 and has a dial indexing rod 26 pivotally secured to its other arm.

The rod 26 has the forward end thereof pivoted to an indexing lever 30 oscillatable about a bearing 31 mounted upon the bed 12. The lever 30 has pivotally secured thereto a pawl 32 which cooperates with a ratchet 33 whereby upon each reciprocation of the rod 26 the ratchet 33 will be rotated one step. Secured to the ratchet 33 is a locking plate 34 which cooperates with a suitable locking pin (not shown) to accurately position a dial 35 secured thereto in a predetermined angular position each time the pawl 32 and ratchet 33 are operated. The dial 35 is rotatably mounted on an upward extension 29 of the bearing 31.

The intermittent rotary motion imparted through the pawl and ratchet mechanism serves to carry headed articles 36 shown in dot and dash lines in Figs. 3, 4, 5 and 6 to a position to be operated upon by the ram 14, which position is indicated generally by the numeral 37. The tools for operating upon the headed articles have not been disclosed since they do not form a part of the present invention. The operation performed by the ram includes the flattening of the tip 38 (Fig. 4) of the article 36 which comprises a shank 39, a tip 38 and a shoulder 40.

Positioned upon a portion of the bed 12 is a hopper 50 in which a number of articles 36 to be worked upon may be placed and from which the articles may be transferred by a suitable oscillating lever (not shown) to a chute indicated generally by the numeral 51. This chute is composed of a pair of plates 52 between which the shank 39 of the articles will lie and upon the upper surface of which the shoulder 40 of the article will rest. A cooperating angle member 53 is provided for holding articles in the chute. The upper ends of the plates 52 and angle member 53 (Fig. 1) are suitably secured to the hopper 50, and at their lower end (Fig. 1) as more clearly shown in Fig. 3 they are secured to each other, suitable spacers being provided at 54 and 55 and the plates 52 and angle member 53 are secured to a support 56.

Extending around the dial 35 is a retaining ring 62 one purpose of which is to hold the articles 36 in nests 63 formed in the dial while the articles are being advanced to a position to be operated upon by the ram 14, and another pur-

50

45

55

55

pose of which is to support the lower end of the chute, the support 56 being fixed to the retaining ring 62 at 64.

An oscillatable member 65 is pivoted to the portion 29 of the bearing 31 at 66 being held in place upon an upwardly extending portion 67 of the bearing by a retaining nut 68. This oscillatable member 65 extends to the left (Fig. 3) from its bearing and is then bent downwardly as shown at 69 and is provided with a horizontally extending portion 70 which extends under the chute 51. A nest 71 is formed in the oscillatable member 65 into which parts from the chute 51 will be dropped when the oscillatable member 65 is in a predetermined position. The corners of the nest 71 are tapered as shown at 83 to guide the articles 36 dropped from the chute 51 into the lower portion of the nest 71.

The nest 71 in the oscillatable member is in the form of an irregularly shaped slot adapted to receive articles 36 from the chute 51 to transfer the articles to the nests 63 in the dial 35. A guide member 80 is secured between the retaining ring 62 and the support 56 to prevent articles 36 from dropping through the nest 71 while the oscillatable member 65 is in the position shown in Figs. 2, 3 and 6. This guide member 80 has a groove 81 formed therein in which the head 40 of the article 36 may roll or slide when the oscillatable member 65 is oscillated thereby to guide the articles 36 to a position at the end of the anti-clockwise oscillation of member 65 where the nest 71 will be in direct vertical alignment with the nest 63 in the dial 35, a stop member 82 being provided to facilitate the directing of the articles 36 from nest 71 to nests 63. The oscillatable member 65 is made wide enough at its left end (Fig. 2) to extend over two nests 63 in the dial 35.

Extending outwardly from the oscillatable member 65 is an arm 84 which has a bearing 85 formed therein for receiving an upwardly extending portion 86 of an actuating member 87. The actuating member 87 has an aperture 88 formed therein in which is loosely positioned a rod 89 secured by means of clamping members 90—90 to the rod 26. Encircling the rod 89 are a pair of coiled springs 91 and 92 which are held under compression against the actuating member 87 by a stop member 93 and lock nuts 94—94, respectively. In order that the pressure which the cooperating springs 91 and 92 exert upon member 87 may be equalized to compensate for fatigue in either one or other of the springs 91 and 92, adjusting means is provided comprising a dowel 100 which may be placed in any one of a plurality of holes 101 to vary the pressure of spring 91 on the actuating member 87 and the lock nuts 94—94 may then be adjusted to properly position the actuating member 87.

A better understanding of the invention will be had from the following description of the operation of the mechanism: Let it be assumed that a plurality of articles 36 have been placed in the hopper 50 and the drive mechanism (not shown) for the punch press has been started. Articles 36 may be fed from the hopper 50 in any well known manner, and positioned in the chute 51 with the shanks 39 of the articles hanging between the cooperating plates 52 and with the shoulders 40 of the articles engaging the upper surfaces of the plates 52 as shown in dot and dash lines (Figs. 3 and 4). The articles 36 will then slide down the chute 51 and be tilted from a

substantially vertical position to a substantially horizontal position as clearly shown in Fig. 3.

Each time the ram 14 is reciprocated the crank wheel 23 will cause the rod 24 to be reciprocated, thereby through the bell crank lever 25 imparting a reciprocating motion to the rod 26, to rotate the dial 35 in a counter-clockwise direction (Fig. 2), to carry parts which had previously been deposited in the nests 63 around to the position to be worked upon as indicated generally by the numeral 37. Each time the rod 26 is moved to drive the dial 35 in a counter-clockwise direction, it will carry with it rod 89 and will tend to move the arm 84 and its associated oscillatable member 65 in a counter-clockwise direction. If for any reason an article 36 has got out of position, the rod 89 will be moved but the spring 91 will be compressed and the arm 84 and oscillatable member 65 will not be moved. However, in the normal operation of the machine the arm 84 will be actuated each time the rod 26 is actuated. The normal position of the oscillatable member 65 is as is shown in Fig. 2 where the nest 71 in the oscillatable member is directly in alignment with the chute 51 so that articles 36 which have moved down to chute 51 will drop into the nest 71 and when the oscillatable member 65 is moved in a counter-clockwise direction, the article 36 in the nest 71 will be carried to a position where the nest 71 and the nests 63 in the dial 35 are in direct vertical alignment whereupon the article will drop into the nest 63, being prevented from jumping out of position by the stop member 82.

The position where the dial nest 63 and the nest 71 in the oscillatable member 65 are in direct vertical alignment is the position at the end of the stroke of the pawl 32. When the pawl 32 is retracted to engage another notch in the ratchet 33, the oscillatable member 65 will be retracted to the position shown in Fig. 2 and another article 36 will drop from the chute 51 into the nest 71. It will be noted that the guide member 80 extends to the right (Fig. 6) to the edge of the first nest 63 to the right of the nest under the chute 51 whereby the article carried in the nest 71 cannot drop into the nest 63 until the end of the stroke of the pawl 32.

What is claimed is:

1. In an article handling apparatus, a movable work table having nests for receiving articles to be worked upon, means for indexing said table, a chute for feeding the articles, a movable member having a recess for receiving articles from the chute, and means operating in timed relation to said indexing means for moving said recessed member in the direction of movement of the table to deposit the articles in said nests.

2. In an article handling apparatus, a rotatable dial having dial nests for receiving articles to be worked upon, means for intermittently rotating said dial, an oscillatable member for depositing articles in said dial nests, a chute for feeding articles to said oscillatable member, and resilient means for moving said oscillatable member about the axis of rotation of the dial from operative relation with said chute to a position to deposit articles in a dial nest.

3. In an article handling apparatus, a rotatable dial having dial nests for receiving articles to be worked upon, means for intermittently rotating said dial, an oscillatable member for depositing articles in said dial nests, a chute for feeding articles to said oscillatable member, and resilient means operated by the means for rotating the

- dial for moving said oscillatable member in an arcuate path about the axis of rotation of the table from operative relation with said chute to a position to deposit articles in a dial nest.
- 5 4. In a feeding mechanism for a punch press having an intermittently rotated dial provided with dial nests for carrying parts to the press, a chute for receiving headed articles to be worked upon by the punch press, means for imparting an intermittent rotation to the dial, an oscillatable member having an article receiving nest therein, a guide member positioned beneath the oscillatable member for holding an article in the nest of the oscillatable member, and resilient means interconnecting the rotating means of the dial and the oscillatable member for oscillating the oscillatable member to move its article receiving nest into position to receive an article from said chute and to a position in alignment with a nest in the dial.
- 10 5. The combination with a punch press having an intermittently rotated dial and means for imparting intermittent rotation to said dial, of a chute for guiding articles to a predetermined position above said dial and in vertical alignment with a nest in said dial, an oscillatable member for receiving parts from said chute and transferring them in an arcuate path while holding them above said dial nest during its movement to a position to be received by said dial, and means interconnecting the means for imparting intermittent rotation to the dial and said oscillatable member to drive said oscillatable member.
- 15 6. The combination with a punch press having an intermittently rotated dial and means for imparting intermittent rotation to said dial, of a chute for guiding articles to a predetermined position with respect to said dial, an oscillatable member for receiving parts from said chute and transferring them to a position to be received by said dial, and means comprising a rod connected to the means for intermittently driving the dial and a member slideable on said rod, said slideable member being held in a central position on said rod by compensating coiled springs and being fixed to said oscillatable member to intermittently tend to oscillate the oscillatable member.
- 20 7. In an article handling apparatus, a rotatable dial having dial nests for receiving articles to be worked upon, means for intermittently rotating said dial, an oscillatable member for carrying an article in alignment with a dial nest movement of the member and dial for depositing articles in said dial nests, a guide member positioned between the oscillatable member and the dial to prevent articles from dropping out of the oscillatable member until the dial nest and oscillatable member are in a predetermined position, a chute for feeding articles to said oscillatable member, and resilient means for moving said oscillatable member from operative relation with said chute to a position to deposit articles in a dial nest.
- 25 8. In an article handling apparatus, a rotatable dial having dial nests for receiving articles to be worked upon, means for intermittently rotating said dial, an oscillatable member for depositing articles in said dial nests, a chute for feeding articles to said oscillatable member, resilient
- means for moving said oscillatable member from operative relation with said chute to a position to deposit articles in a dial nest comprising a rod secured to the means for rotating the dial, a pair of cooperating springs mounted on said rod, and an actuating member positioned between said springs and fixed to the oscillatable member.
- 30 9. In an article handling apparatus, a rotatable dial having dial nests for receiving articles to be worked upon, means for intermittently rotating said dial, an oscillatable member for depositing articles in said dial nests, a guide member positioned between the oscillatable member and the dial to prevent articles from dropping out of the oscillatable member until the dial nest and oscillatable member are in a predetermined position, a chute for feeding articles to said oscillatable member, resilient means for moving said oscillatable member from operative relation with said chute to a position to deposit articles in a dial nest comprising a rod secured to the means for rotating the dial, a pair of cooperating springs mounted on said rod, and an actuating member positioned between said springs and fixed to the oscillatable member.
- 35 10. In an article handling apparatus, a rotatable dial having dial nests formed therein for receiving articles to be worked upon, a stationary retaining ring for holding parts in the dial nests during rotation of the dial, actuating means for imparting a step by step rotation to the dial, a chute for feeding parts to a predetermined position, an oscillatable member cooperating with and positioned below said chute and having a nest formed therein for receiving parts from said chute, a guide plate fixed to the retaining ring and interposed between the oscillatable member and the dial to prevent articles in the nest of the oscillatable member from passing to the dial nests in predetermined positions of the oscillatable member, a resilient means interconnecting the actuating means for the dial with the oscillatable member, and a stop member fixed to the retaining ring for guiding an article from the nest in the oscillatable member to a dial nest.
- 40 11. In an article handling apparatus, a rotatable dial having dial nests for receiving articles to be worked upon, means for intermittently rotating said dial, an oscillatable member for depositing articles in said dial nests, a stationary chute for feeding articles to said oscillatable member, and a resilient means interconnecting said oscillatable member and dial rotating means for moving said oscillatable member in the same arcuate path as the dial to carry an article from the chute to a dial nest.
- 45 12. In an article handling apparatus, a rotatable dial having dial nests for receiving articles to be worked upon, means for intermittently rotating said dial, an oscillatable member for depositing articles in said dial nests, a stationary chute for feeding articles to said oscillatable member, and resilient means interconnecting said oscillatable member and dial rotating means for moving said oscillatable member in the same arcuate path as the dial and in a plane parallel to the plane of movement of the dial to carry an article from the chute to a dial nest.
